CLAIM

The ornamental design for a jewelry organizer, as shown and described.

DESCRIPTION

FIG. 1 is a front perspective view of a jewelry organizer showing our new design;

FIG. 2 is a front perspective view of the jewelry organizer of FIG. 1 with one of the doors open;

FIG. 3 is a rear perspective of the jewelry organizer of FIG. 1;

FIG. 4 is a side view of the jewelry organizer of FIG. 1 looking from the right side thereof;

FIG. 5 is a plan view of the jewelry organizer of FIG. 1; and

FIG. 6 is a front perspective view of a jewelry organizer showing a second embodiment of our design on an enlarged scale and showing one compartment in open position.

FIG. 1

FIG. 2

FIG. 4
